UNITED STATES PATENT OFFICE.

STANISLAW PTAK AND ALOIS SADLIK, OF KEWANEE, ILLINOIS.

MAIL-BOX.

1,144,566.

Specification of Letters Patent. Patented June 29, 1915.

Application filed January 4, 1915. Serial No. 325.

To all whom it may concern:

Be it known that we, STANISLAW PTAK and ALOIS SADLIK, subjects of the Emperor of Austria-Hungary, residing at Kewanee, 5 in the county of Henry and State of Illinois, have invented certain new and useful Improvements in Mail-Boxes, of which the following is a specification.

This invention relates to certain new and 10 useful improvements in mail boxes.

The primary object of this invention is to provide a mail box having the smallest possible number of parts, although adapted 15 to protect the mail matter from any unauthorized removal, such construction being easy and cheap to manufacture.

A further object is to provide a mail box having a combined mail slide and slot protector which is shiftably positioned 20 through the mail entrance slot of the box, and although normally closing the slot may be readily moved for conducting mail matter therethrough and into the protected deposit chamber of the box.

25 With these general objects in view and others that will appear as the nature of the invention is better understood, the same consists in the novel combination and arrangement of parts hereinafter more fully described, illustrated in the accompanying drawings and pointed out in the appended claims.

In the drawings forming a part of this application and in which like-designating 30 characters refer to corresponding parts throughout the several views, Figure 1 is a front elevation of the mail box. Fig. 2 is a side elevation thereof, the casing being partially shown in vertical transverse 40 section and with the device closed. Fig. 3 is a vertical transverse sectional view through a portion of the box, the elements being shown in their mail-receiving position, and Fig. 4 is a horizontal transverse 45 sectional view through the forward portion of the box and with the slide partly broken away.

Referring more in detail to the drawings, 50 the invention herein contemplates the provision of a mail box or receptacle 10 of substantially the usual form having a curved top 11 and a hinged side door 12 positioned adjacent the bottom of the box for allowing the removal of the mail upon 55 disengaging the lock 13.

The mail box is provided with an en-

trance slot 14 in the front wall 15 thereof and the protecting bead or strip 16 projects over the outer surface of said front wall slightly above the slot 14. A mail 60 slide 17 is shiftably positioned through the slot 14 and has a row of spaced fingers 18 upon its inner edge, while a plate 19 is obliquely secured to the outer edge of the slide which is adapted for flatly engaging 65 the front wall 15 and completely closing the entrance slot when the slide is inoperatively positioned. Oppositely projecting pins 20 are carried by the slide 17 within the box which prevent the complete withdrawal of the slide through the slot. The plate 19 has an outwardly projecting central handle 21 whereby the slide may be projected through the slot from the position shown in Fig. 2 to that illustrated in Fig. 70 75 3, and in which latter position it will be evident that a letter such as 22 may be flatly positioned upon the slide 17 inwardly of the angular projecting upper portion of the plate 19 so that when the slide is pushed 80 inwardly and downwardly until it rests in its normal oblique position upon the opposite lugs 23 of the casing, the mail matter will be precipitated over the slide and will fall into the deposit receptacle within 85 the lower portion of the box.

A guard plate 24 is obliquely secured within the box at the upper rear angle 25 thereof and is provided with spaced fingers 26 at its lower free edge adapted for slidably meshing with the fingers 18 of the slide 90 during the inward movement of the latter, it being noted that the free ends of the slide and guard fingers are positioned substantially upon the central vertical axis of the 95 box when the slide is in its closed position as best illustrated in Fig. 2, at which time also the plate 19 is in its closed engagement over the entrance slot and in contact with the lower face of the protecting bead 16. 100

From this detailed description of the device, it will be seen that when the box is closed as shown in Fig. 2, it will be impossible to open the same by means of the slide to such an extent that the hand can be inserted for the unauthorized removal of mail matter within the box as the withdrawal of the slide requires the passing of the slide fingers 18 through the fingers of the guard 24. When a letter is placed upon the open 110 slide and the slide is pushed into the box, the letter falling into the receptacle will be

prevented from removal except by opening the door 12 as the guard and slide fingers are positioned above the receiving chamber for the mail matter.

5 While the form of the invention herein shown and described is what is believed to be the preferred embodiment thereof, it is nevertheless to be understood that minor changes may be made without departing 10 from the spirit and scope of the invention as set forth in the claims.

What is claimed as new is:—

1. A mail box provided with an entrance slot in one wall thereof, a projecting bead 15 positioned thereabove, a fingered guard inwardly inclined and secured within the box, a shiftable slide positioned through said slot and having spaced fingers upon its inner edge, and a slot closing plate angularly secured to the outer end of the said slide.

2. In combination with a mail box provided with an entrance slot in the front wall thereof, a projecting bead secured to said 25 wall above the said slot, an oblique inwardly projecting guard secured within said box at the upper rear angle thereof, and terminating in spaced fingers at its free edge, inwardly projecting opposite oblique 30 lugs carried by the end walls of the box, a

slide shiftably positioned through the said slot and having spaced fingers upon its inner free edge, projecting stop pins at the opposite edges of the said slide within said box, a slot closure plate obliquely secured to the outer end of the said slide and positioned in flat engagement with the front wall of the box beneath the said bead and overlying the said slot when the slide is normally positioned in flat engagement with the said lugs and an operating handle secured to the said plate. 35

3. In a mail box having an entrance slot, a normally positioned combined mail slide and slot closure member projecting obliquely 45 inwardly of the box through the said slot thereof, an inclined guard within the said box positioned within the path of movement of the said member, the inner ends of the said guard and slide member being normally positioned upon substantially the central vertical axis of the box. 50

In testimony whereof we affix our signatures in presence of two witnesses.

STANISLAW PTAK.
ALOIS SADLIK.
